(57) **CLAIM**

The ornamental design for a display screen or portion thereof with graphical user interface, as shown.

DESCRIPTION

FIG. 1 is a front view of a display screen with a graphical user interface showing a first image of a sequence for our new design;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The appearance of the transitional image sequentially transitions between the images shown in FIGS. 1-7. The process or period in which one image transitions to another image forms no part of the claimed design.

Broken lines shown in the figures illustrate a display screen or portion thereof, and form no part of the claimed design. Other broken lines shown in the figures illustrate portions of a graphical user interface that form no part of the claimed design.
